WIRE-STRETCHING DEVICE

John P. Wyatt, Raleigh, N. C.

Application April 22, 1949, Serial No. 89,028

3 Claims. (Cl. 254—77)

1

This invention relates to a novel construction of wire stretcher, particularly adapted for use in stretching single strands or woven fence wire and which may be effectively employed by one operator for rapidly stretching wire with a minimum of manual effort and for effectively holding the wire under tension while it is stapled to a fence post, tree trunk or other upright anchoring member.

Another object of the invention is to provide a wire fence stretcher having a novel means for clamping the wire therein.

A further object of the invention is to provide a wire stretcher which is adapted to slide relatively to a leverage means thereof to cause the wire to be automatically displaced into a position against a post or other upright, employed as a fulcrum for the leverage means and so that the wire may be readily anchored to said upright while held under tension.

Still another object of the invention is to provide a wire stretcher of extremely simple construction capable of being economically manufactured and sold and which will be extremely efficient and durable for accomplishing its intended purpose.

Various other objects and advantages of the invention will hereinafter become more fully apparent from the following description of the drawing, illustrating preferred embodiments thereof, and wherein:

Figure 1 is a top plan view of the assembled wire stretcher and showing a portion of a strand of wire engaged thereby;

Figure 2 is a longitudinal horizontal sectional view thereof;

Figure 3 is a cross sectional view of the wire stretcher taken substantially along a plane as indicated by the line 3—3 of Figure 1;

Figure 4 is a perspective view showing the wire stretcher in use, and

Figure 5 is a view similar to Figure 4 and illustrating a slightly different embodiment of the wire stretcher.

Referring more specifically to the drawing and particularly with reference to Figures 1 to 4 thereof, the novel wire stretcher in its entirety is designated generally 6 and includes a T-shaped coupling, designated generally 7 and a leverage member, designated generally 8.

The T-shaped coupling member 7 comprises a longitudinal sleeve portion 9 and a transverse sleeve portion 10 which is formed integral with an intermediate portion of the sleeve 9 and which projects laterally therefrom. The transverse

sleeve 10 is internally threaded as seen at 11 at its outer end to receive a threaded plug 12 which may be provided at its outer end with a restricted shank 13 of non-circular cross section for receiving a turning tool, not shown. The sleeve 10, contiguous with its threaded portion 11 is provided with an outwardly opening substantially V-shaped notch 14 which is preferably beveled on the external side of said sleeve 10 and through

which a portion of a strand of wire 15 is adapted to extend; the wire strand 15 being applied to the notch 14 when the plug 12 is removed or backed off and after which the plug 12 is applied or advanced into the threaded sleeve portion 11 for clamping the wire strand 15 in the inner end of the V-shaped notch 14 to thereby anchor the strand 15 to the wire stretcher 6.

The lever 8 includes a length of pipe 16 and a length of pipe 17 of a larger internal and external diameter than the pipe 16. The pipe 16 is provided with an externally threaded end 18 which may be externally enlarged and which is adapted to detachably engage the internally threaded end 19 of the pipe 17. The remote ends of the pipes 16 and 17 are externally threaded as seen at 20 and 21, respectively, to receive the internally threaded caps or closures 22 and 23, respectively. The connected pipes 16 and 17, with the closures 22 and 23 applied thereto provide a housing which may be utilized for holding a staple removing tool 24, as seen in Figure 2.

The pipe 21 is of a diameter to slidably and detachably engage the longitudinal sleeve 9 of the coupling 7 and the pipe 17 is of a larger diameter than the bore of the sleeve 9 and its first mentioned, internally threaded end is adapted to normally abut against one end of said sleeve 9. Assuming that the coupling 7 is thus applied to the pipe 16 of the lever 8 and that the wire strand 15 is clamped in the coupling 7, as previously described, the other, exposed end of the pipe 16 is placed against a stationary upright such as a fence post or tree trunk 25, as illustrated in Figure 4 and which is used as a fulcrum for the lever 8 and by engagement with said last mentioned end of the pipe 16. The pipe 17 is employed as a handle and is swung in the direction as indicated by the arrow in Figure 4 for stretching the fence strand 15 and as said lever 8 is thus swung beyond its position of Figure 4 the coupling 7 will slide on the pipe 16 toward the post or tree trunk 25 to position a portion of the strand 15 against said upright 25 and so that after the strand 15 has been stretched to the desired extent and while being held under tension,

it may be secured by a staple or other fastening, not shown, to the upright 25.

A slightly modified form of the wire stretcher, designated generally 6a is illustrated in Figure 5 and for use in stretching woven fence wire and wherein two or more of the T-shaped couplings 7 are employed, each of which is connected to a longitudinal strand of the woven wire fence 26 in the same manner that the single strand 15 is anchored to the coupling 1, as illustrated in Figures 1 to 3 and as previously described. A rod or pipe 27 is then passed through the sleeve portions 9 of the couplings 7 and disposed in an upright position so that said sleeve portions will be disposed substantially vertically, instead of substantially horizontally as illustrated in Figures 1 to 4. Two rods or pipes 28 are then disposed as seen in Figure 5 with portions thereof engaging against the rod 27 and with corresponding ends thereof bearing against the post or trunk 25 to fulcrum thereon when the rods or levers 28 are swung in a direction as indicated by the arrows in Figure 5 for stretching the woven wire 26 and for causing the rod 27 and the couplings 7 carried thereby to slide on the levers 28 toward the post or trunk 25 after said levers have passed a point at right angles to the plane of the woven wire 26, and so that the woven wire can be stapled or otherwise fastened to the upright 25 while held under tension by the levers 28.

Various modifications and changes are contemplated and may obviously be resorted to, without departing from the spirit or scope of the invention as hereinafter defined by the appended claims.

I claim as my invention:

1. A wire stretcher comprising a sleeve member, wire clamping means forming a part thereof and projecting laterally therefrom and adapted to detachably clamp a strand of wire therein, and a leverage member having end sections of different external diameters, one of said end sections being sized to slidably and detachably engage in the sleeve member, the other leverage section being of larger diameter than the sleeve bore and forming a stop for limiting the sliding movement

of the sleeve in one direction relatively to the leverage member, and the opposite end of the smaller section of the leverage member being adapted to be fulcrumed against a stationary upright member relatively to which the leverage member is swung in a direction for stretching the wire and for positioning the leverage member so that said sleeve member will slide thereon toward the stationary upright.

10 2. A wire stretcher as in claim 1, said sleeve member and its wire clamping means comprising a substantially T-shaped coupling having a plug for detachably and adjustably engaging the outer end of the lateral leg thereof, and said lateral leg of the coupling having an outwardly opening V-shaped notch adapted to receive the wire strand and in which the strand is clamped by the plug when the latter is moved to an advanced position.

20 3. A woven wire fence stretcher comprising a plurality of wire clamping members each adapted to be detachably clamped to a longitudinal strand of a length of woven fence wire, said wire clamping members having sleeve portions, an elongated rigid member detachably engaging each of said sleeve portions and disposed substantially in an upright position, and a plurality of elongated levers having corresponding ends adapted to be fulcrumed against a stationary upright member and having other corresponding portions thereof engaging said elongated rigid member for displacing said rigid member and the wire engaging members in a direction for tensioning the woven fence wire when said levers are swung in one direction on their fulcrumed ends.

35 JOHN P. WYATT.
